(Cl. D58—11)

FIG. 1

FIG. 2

FIG. 3

FIG. 4

Fig. 1 is a perspective front elevational view of a container for a cigarette lighter or the like, showing my new design;

Fig. 2 is a similar view with the cover in open position;

Fig. 3 is a top view; and

Fig. 4 is a bottom view.

The broken lines indicate that the trim at the junction of the two halves of the container is in fact continuous. It is to be understood that the portions stippled in full lines continue throughout the areas represented by light lines.

I claim:

The ornamental design for a container for a cigarette lighter or the like, substantially as shown and described.
